CURTAIN ROD SUPPORT

Harvey J. Reedy and Joseph P. Marucco,
San Francisco, Calif.

Application June 17, 1938, Serial No. 214,238

1 Claim. (Cl. 248—265)

This invention relates to improvements in curtain rod supports and has particular reference to a support which may be employed for raising or lowering the curtain rod so that the curtain may be readily placed and removed therefrom.

A further object is to produce a device of this character which will be neat in appearance, economical to manufacture, and a device which will be free from projections which might damage lacy curtains.

Other objects and advantages will be apparent during the course of the following description.

In the accompanying drawing forming a part of this specification and in which like numerals are employed to designate like parts throughout the same,

Fig. 1 is a front plan view of our device as the same would appear when mounted upon a window casing;

20 Fig. 2 is an enlarged fragmentary view;

Fig. 3 is a cross sectional view taken on the line 3—3 of Fig. 2;

Fig. 4 is a cross sectional view taken on the line 4—4 of Fig. 1; and

25 Fig. 5 is a fragmentary perspective view showing the slider arrangement.

The ordinary window curtains are supported upon rods mounted upon brackets adjacent the upper extremity of the window casing. As a result of this construction, it is necessary for the person placing the curtains on the rods to stand on a ladder, chair, or the like in order to perform this function. Many serious accidents have occurred on this account, and applicants have, therefore, devised a curtain rod support which is 30 slidable and permits the rod or rods to be lowered to a height where the person may readily place or remove the curtains from the rods without the employment of a stepladder or the like to stand upon.

40 In the accompanying drawing wherein for the purpose of illustration is shown a preferred embodiment of our invention, the numeral 5 designates a window frame upon which our device is mounted. This frame may be rabbeted out as shown at 6 so that the track of the device may be flush with the surface of the window casing, if desired. However, this is not necessary but makes an attractive installation.

45 Our device consists of a track 7 so constructed as to have a channel 8 and flared edges 9 and 11. These flared edges 9 and 11 serve to support a runner 12, which runner is attached to the upper end of the bar 13, which bar has an outwardly turned end 14, and an opening 16 is formed therethrough so as to engage a tongue 17 punched from the track 7. A friction block 18 is secured near the bottom of the track, and a guard 19 is secured to the lower end of the track

and maintains the bar in contact with its friction block while the device is being lowered. Brackets 22, secured to the runner 12, are freely movable about their pivotal connection so that the curtain rod may be swung to a vertical position, if desired, without danger of bending the same.

In Fig. 3 we have shown the use of two rods A and B. It is, of course, obvious that one could be used if desired.

The result of this construction is that when the parts are in the position of Fig. 1 and it is desired to place curtains upon the rods A and B, the operator takes hold of the outwardly turned end 14 and lifts the same slightly against gravity, thus disengaging the tongue 17 from the opening 16, after which the end of the bar is moved outwardly, as shown in dotted lines in Fig. 4, and dropped any desired distance.

It is, of course, obvious that the opposite side of the window is adjusted in the same manner. By having the brackets 22 movable, this up and down movement may be accomplished without any binding or twisting effect upon the rods. There is sufficient tension between the guard 19 and the friction block 18 to permit stoppage at any point in the travel so that the operator may adjust the rod to any desired height for easy adjustment.

It is to be understood that the form of our invention herewith shown and described is to be taken as a preferred example of the same and that various changes relative to the material, size, shape and arrangement of parts may be resorted to without departing from the spirit of the invention or the scope of the subjoined claim.

Having thus described our invention, we claim:

In a device of the character described, a supporting track mounted adjacent one side of a window and embodying in its construction a channel having outwardly flared edges, a slide movable on said flared edges, a bar mounted in said channel and secured to said slide, said bar being flush with the outer surface of said channel, the lower end of said bar being bent at an angle of 90° and having an opening formed therethrough at the bend thereof, a tongue struck from said channel adjacent its lower end and capable of entering said opening in said bar when said bar is at its upper limit of travel, a guard mounted on said track and spaced from said bar a sufficient distance to permit said bar to be moved forwardly to disengage from said tongue when said bar is to be moved downwardly in said channel, and a friction bar interposed between said track and said bar to retard the dropping of said bar during the lowering operation.
